STARTING MECHANISM FOR INTERNAL COMBUSTION ENGINES

Jasper F. Cullin, Detroit, Mich., assignor of two-thirds to Lou Mervis, Lock Haven, Pa.

Application July 3, 1940, Serial No. 343,762

12 Claims. (Cl. 74—116)

The invention relates to starters for internal combustion engines.

The objects of the invention are to provide a starting mechanism which is adapted for operation at a high gear ratio relatively to the crank shaft; in which the possibility of locking of the gearing is avoided; in which the gearing is positively disengaged when the engine is started; and which is compact and light in construction.

Other objects of the invention will appear from the detail description.

The invention consists in the several novel features which are hereinafter set forth and are more particularly defined by claims at the conclusion hereof.

In the drawings: Fig. 1 is an end elevation of starting mechanism embodying the invention; Fig. 2 is a side elevation, the gear-case being shown in section; Fig. 3 is a transverse section on line 3—3 of Fig. 2, the starting mechanism being shown in its operative position; Fig. 4 is a horizontal section taken on line 4—4 of Fig. 1; Fig. 5 is a section showing the starting mechanism disengaged; Fig. 6 is a section on line 6—6 of Fig. 5; Fig. 7 is a diagrammatic view of the electrical connections for the electric starting motor and the control circuits; Fig. 8 is a section illustrating the shaft of the electric starting motor and a modified form of the invention in which the eccentrics are driven by the motor through a resilient or cushioned connection.

The invention is exemplified with the shaft 10 of an internal combustion engine which may be of any type. A gear-case 11 encloses one end of the crank shaft and the gearing for driving the crank shaft from an electric motor 12. The axis of the shaft 13 of motor 12 is parallel to the axis of the engine-shaft 10. The casing of the motor 12 is provided with a flange 121 which is secured by bolts 15 to one side of the gear-case 11. The inner end of the motor-casing and the shaft 13 extends into the gear-case 11.

A ratchet-wheel 16 is mounted on the engine-shaft 10 to drive said shaft in one direction through an overrunning clutch 17.

The mechanism for driving shaft 16 from electric motor 12 to start the engine comprises a pair of eccentrics 18 and 19 which are keyed to the shaft 13 of motor 12 and are positioned so their throws will be 180° apart. The eccentrics are spaced apart and held against longitudinal movement on shaft 13 by washers 20 and 21 and a nut 22 which is threaded to the outer end of shaft 13. Pawls 23 and 24 are respectively journaled on eccentrics 18, 19. Each pawl is pro-

vided with a tooth 25 adapted to successively engage the teeth of ratchet-wheel 16. The setting of the eccentrics 180° apart causes the pawls to alternately impart strokes for rotating the ratchet-wheel, the operative stroke being imparted to one pawl during the retractile stroke of the other pawl. Each pawl is provided with an integral extension 26 which functions as a counterbalance to normally hold the pawl disengaged from ratchet 16. When the electric motor 12 is operated and the pawls are held in engagement with ratchet-wheel 16 they operate alternately to rotate the ratchet-wheel at a high gear ratio, each one-half revolution of each eccentric imparting movement to the ratchet-wheel 16 a distance corresponding to the spacing between the teeth of wheel 16.

The operation of the pawls is controlled by a pair of arms 28 and 29 which are formed of spring-metal and are normally positioned to allow the counterweights 26 to lift teeth 25 of the pawls out of engagement with the ratchet-wheel 16. These arms are manually shiftable to engage pawls with said wheel and to hold them in engagement therewith during the operation of the eccentrics. Resilient arms 28, 29 are fixed to a controller-shaft 30 which carries said arms inside of the gear-case 11, extends through the side wall of said case to the outside thereof and is provided with a handle 31 which may be located at any point within convenient reach of the operator and connected to rock shaft 30. Rotation of shaft 30 will shift arms 28, 29 and engage pawls 23, 24 and ratchet-wheel 16 and 35 will release them for disengagement from said wheel by the counterweights 26 on the pawls.

Shaft 30 also controls the operation of the motor 12 for operating eccentrics 18, 19, through a cam 32 which is adapted to open and close a switch which is mounted on the outside of crank-case 11 and comprises contacts 33, 34 which are insulated from each other, normally disengaged and adapted to be engaged by said cam to close a circuit for causing the motor 12 to operate. 45 This switch is opened and closed by shaft 30 to conjointly control the motor and arms 28, 29 for controlling pawls 23, 24. Contact 33 is connected by a conductor 35 to battery 36. Contact 34 is connected by a conductor 37 to the helix 50 of a solenoid magnet 38 which operates a switch-member 39 for engaging contacts 40, 41 to close a circuit through motor 12 from conductor 35, switch-member 39 and conductor 44. The motor and battery are usually grounded to the frame of the vehicle, as well understood in the art.

When shaft 30 is shifted, resilient arms 28, 29 will first engage the pawls 23, 24 with ratchet 16, and after the pawls are pressed into engagement with the ratchet, contacts 30, 34 will be engaged by cam 32 and establish a circuit through the solenoid-magnet for closing a circuit for the operation of the motor 12. When the engine has been started, the operator shifts handle 31 back to its normal position which will first open the circuit at contacts 33, 34 through the solenoid 38 and open the motor-circuit at switch 39 and stop the motor, and then shift arms 28, 29 for disengaging them from the ratchet-wheel. A stop 46 is provided to limit the throw of shaft 30 and handle 31. The spacing between contacts 33, 34, when shaft 30 is in its normal position, and the starter is inoperative, is such that the pawls will be shifted into engagement with the ratchet in advance of the closing of the circuit for the operation of the starting motor 12. The arms 28, 29 force the pawls into engagement with the ratchet-wheel before the motor-circuit is closed. This causes strong pressure to be applied to the pawls before motor 12 commences to operate in starting and inversely shuts off the current from the motor before the pawls are released. The housing of solenoid-magnet 38 is secured at 48 to the outside of gear-case 11.

When the starter is used with lighter types of engines the overrunning clutch 17 may be omitted and the ratchet-wheel secured directly to the crankshaft 10 so that the engine will be at all times locked against the inertia of a backfire which usually occurs very near the end of the up-stroke. The power then exerted is comparatively low and the pawls will lock the ratchet against reverse rotation.

In heavier types of engines it is sometimes desirable to cushion the starting mechanism and, for this purpose, the construction shown in Fig. 7 is used. In this construction the eccentrics are keyed to a sleeve 50 which is rotatable on shaft 13, a collar 51 is keyed to shaft 13 and a coil-spring 52 has its ends connected as at 53 and 54 to sleeve 50 and collar 51, respectively. This provides a cushioned driving connection between the motor 12 and the pawls in starting heavy engines.

The overrunning clutch 17 is preferably used with heavy engines to allow the engine to turn after it starts and before the pawls are disengaged from ratchet 16 to avoid the riding of the pawls over the notches in the ratchet-wheel between the time the engine starts and the starting switch is opened. This eliminates the noise incident to any delay in stopping the starting motor.

The invention exemplifies a starter for internal combustion engines which avoids any locking between gears, effects positive disengagement of the pawls and ratchet-wheel when stopping the starting motor, operates the engine-shaft, at a very high gear ratio, is compact, light in weight, and simple in construction.

The invention is not to be understood as restricted to the details set forth, since these may be modified within the scope of the appended claims, without departing from the spirit and scope of the invention.

Having thus described the invention, what I claim as new and desire to secure by Letters Patent is:

1. The combination with starting mechanism for internal combustion engines, comprising a ratchet-wheel connected to drive the crank shaft and engine, an electric motor, eccentrics driven

by the motor, and pawls journaled on said eccentrics for driving the wheel, of resilient means for shifting the pawls into engagement with the wheel, a switch for controlling the motor, a control-shaft, on which the pawl shifting means is mounted, and switch-controlling means on said control-shaft.

2. The combination with starting mechanism for internal combustion engines, comprising a ratchet-wheel connected to drive the crank shaft of an engine, an electric motor comprising a shaft mounted in parallel relation with the crank shaft, eccentrics on, and driven by, said motor-shaft, and pawls journaled on said eccentrics for driving the wheel, of a manually operable control-shaft, resilient arms on said control-shaft for shifting the pawls into engagement with said wheel, and means on the control shaft for controlling the operation of the motor.

3. The combination with starting mechanism for internal combustion engines, comprising a ratchet-wheel connected to drive the crank shaft of an engine, an electric motor comprising a shaft mounted in parallel relation with the crank shaft, eccentrics on, and driven by, said motor-shaft, and pawls journaled on said eccentrics for driving the wheel and provided with counterweights, of a manually operable control-shaft parallel to the motor-shaft, resilient arms on said control-shaft for shifting the pawls into engagement with said wheel, and means for controlling the operation of the motor.

4. The combination with starting mechanism for internal combustion engines, comprising a ratchet-wheel connected to drive the crank shaft of an engine, an electric motor comprising a shaft mounted in parallel relation with the crank shaft, eccentrics on, and driven by, said motor-shaft, and pawls journaled on said eccentrics for driving the wheel, of a manually operable control-shaft parallel to the motor-shaft, resilient arms on said control-shaft for shifting the pawls into engagement with said wheel, and means for controlling the operation of the motor.

5. The combination with starting mechanism for internal combustion engines, the combination of a ratchet-wheel connected to drive the crank shaft of an engine, pawls for engaging and operating said wheel, eccentrics on which the pawls are journaled for operating the pawls, and an electric motor comprising a shaft for driving the eccentrics, of manually operable means for engaging the pawls with the wheel, and means for controlling the operation of the motor, comprising a switch controlled by said manually operable means, and an electromagnetic switch.

6. The combination with an engine starter comprising a ratchet wheel adapted to drive the engine, a drive shaft, eccentrics on, and adapted to be driven by, the drive shaft and pawls journaled on the eccentrics for rotating the ratchet wheel, of automatically acting means on the pawls for holding them disengaged from the ratchet wheel, and manually operable means for shifting the pawls to engage the ratchet and controlling the operation of the ratchet.

7. The combination with an engine starter comprising a ratchet wheel adapted to drive the engine, a drive shaft, eccentrics on, and adapted to be driven by, the drive shaft and pawls journaled on the eccentrics for rotating the ratchet wheel, of automatically acting means on the pawls for holding them disengaged from the

ratchet wheel, resilient means for pressing the pawls into engagement with the ratchet wheel, and manually operable means for shifting the resilient means and engaging the pawls with the ratchet and for controlling the operation of the ratchet by the pawls.

8. The combination with an engine starter comprising a ratchet wheel adapted to drive the engine, a drive shaft, eccentrics on, and adapted to be driven by, the drive shaft, and pawls journaled on the eccentrics for rotating the ratchet wheel, of weights on the pawls for automatically holding them disengaged from the ratchet wheel, resilient means for pressing the pawls into engagement with the ratchet wheel, and manually operable means for shifting the resilient means for engaging the pawls with and for controlling the operation of the ratchet.

9. The combination with an engine starter comprising a ratchet wheel adapted to drive the engine, pawls for rotating said wheel, eccentrics on which the pawls are journaled, and a drive shaft to which the eccentrics are secured, of automatically acting means on the pawls for disengaging them from the ratchet wheel, a rotatable shaft substantially parallel with the shaft to which the eccentrics are secured, and resilient strips secured to said shaft for shifting the pawls into engagement with the ratchet wheel.

10. An engine starter comprising a ratchet wheel adapted to drive the engine, pawls for rotating said wheel, eccentrics on which the pawls are journaled, a drive shaft to which the eccen-

trices are secured, weights on the pawls for holding them normally disengaged from the ratchet wheel, a rotatable shaft substantially parallel with the shaft to which the eccentrics are secured, and resilient strips fixed to said shaft for shifting the pawls into engagement with the ratchet wheel.

11. The combination with an engine starter comprising a ratchet wheel adapted to drive the engine, pawls for rotating said wheel, eccentrics on which the pawls are journaled, and a motor-driven drive shaft on which the pawls are secured, of means for holding the pawls disengaged from the ratchet, resilient means for shifting the pawls and holding them in engagement with the ratchet wheel, a control shaft substantially parallel with the drive shaft, the resilient means being connected to said control shaft, and means on the control shaft for controlling a switch for controlling the operation of the drive shaft.

12. The combination with an engine starter comprising a ratchet wheel adapted to drive the engine, a drive shaft, eccentrics on the drive shaft, pawls for rotating said wheel journaled on the eccentrics, of a manually operable control shaft substantially parallel with the drive shaft, means for automatically holding the pawls disengaged from the ratchet, and resilient strips having their inner ends fixed on the control shaft for engaging the pawls and holding them engaged with the ratchet wheel.

JASPER F. CULLIN.
